United States Patent Office.

ALONZO FRENCH, OF PHILADELPHIA, PENNSYLVANIA.

Letters Patent No. 95,102, dated September 21, 1869.

IMPROVEMENT IN INSTRUMENTS FOR TIGHTENING AND LOOSENING SCREW-CAPS OF FRUIT-JARS.

The Schedule referred to in these Letters Patent and making part of the same.

To all whom it may concern:

Be it known that I, ALONZO FRENCH, of Philadelphia, Pennsylvania, have invented an Instrument for Loosening and Tightening the Screw-Caps of Fruit-Jars; and I do hereby declare the following to be a full, clear, and exact description of the same.

My invention consists of two handled jaws, hinged together, and having in their inner edges a screw-thread, adapted to a corresponding thread on the flexible metal rings of fruit-jars, the whole, which is fully described hereafter, forming an instrument by which the said ring may be readily tightened and loosened, without being distorted or otherwise wounded.

In order to enable others to make and use my invention, I will now proceed to describe its construction and operation, reference being had to the accompanying drawing, which forms a part of this specification, and in which—

Figure 1 is a perspective view of my instrument for loosening and tightening the screw-rings of preserving-vessels;

Figure 2, a view of the screw-ring and part of the vessel, with the instrument in section;

Figure 3, a view of the instrument as it appears when open; and

Figure 4, a modification of the instrument.

A represents the upper portion of a fruit-jar, and B the metallic screw-ring, for confining the cover D to the mouth of the jar.

This ring is made of thin metal, and has a screw-thread formed on it, to correspond with that formed on the glass jar, below the mouth of the same.

Heretofore it has been the practice, in removing and replacing these screw-rings, to rely upon the force applied by the hand which grasps the ring. While this force may suffice to tighten the ring and compress

the cover to its packing, the loosening of the ring frequently demands a force which cannot be imparted by the hand, but which can easily be exercised by the aid of my improved instrument.

This consists of two semi-annular or nearly semi-annular jaws E and E', hinged together at x, each jaw being provided with a handle, e, or the handled jaws may be made and hinged together, as shown in fig. 4.

In the inner edge of the jaws is formed a screw-thread, corresponding with that on the exterior of the screw-ring B, so that after opening the jaws, and placing the instrument over the top of the jar, and then closing the jaws by means of the handles, the screw-thread of the latter will adapt itself to that of the ring, which is seized with a firm grip by the instrument, the latter forming a lever, by the aid of which the ring may be readily loosened from its bearings or tightened to its packing, and this without distorting or otherwise wounding the ring; for although the latter is of such thin metal as to be flexible, the bearing of the jaws is so distributed throughout the entire exterior of the ring, or nearly so, that the latter cannot yield at one point more than another.

I claim as my invention, and desire to secure by Letters Patent—

The within-described instrument, consisting of two handled jaws, hinged together, and having in their inner sides a screw-thread, adapted to that of a screw-ring for fruit-jars, all substantially as set forth.

In testimony whereof, I have signed my name to this specification, in the presence of two subscribing witnesses.

ALONZO FRENCH.
